UNITED STATES PATENT OFFICE.

HENRY P. KRAFT, OF RIDGEWOOD, NEW JERSEY.

TIRE-VALVE.

1,307,980.

Specification of Letters Patent. Patented June 24, 1919.

Application filed September 1, 1915. Serial No. 48,389.

To all whom it may concern:

Be it known that I, HENRY P. KRAFT, a citizen of the United States of America, residing in Ridgewood, in the county of Bergen and State of New Jersey, have invented 5 certain new and useful Improvements in Tire-Valves, of which the following is a specification.

This invention relates to tire valves and 10 aims to provide certain improvements therein.

The invention is particularly directed to the well-known Schrader valve and is designed to provide a top guide for the valve 15 whereby to insure that the latter shall be properly seated.

In this type of valve a plug member is provided which screws into the open-ended socket of the valve shell and holds the valve 20 seat in position therein. Such plug member may be formed separately from the seat or may be an integral part thereof. According to the preferred form of the invention the plug member is utilized as a guide for 25 the valve, through the medium of the so-called deflating pin which extends through it. In the usual construction the hole or bore through the plug must be sufficiently large to admit proper quantities of air 30 through the valve in inflating the tire or other device to which the valve is applied. Hence the deflating pin cannot fit so closely as to make a very accurate guide for the valve. In the present invention the plug is 35 formed with a bridge which is provided with a hole of smaller diameter than the main portion of the hole through the plug so that the pin may make a close guiding fit with the bridge, while suitable passages 40 for the air are provided in the sides of the bridge which connect with the main hole through the plug, thus retaining the maximum passage through the latter.

Referring to the accompanying drawings 45 which illustrate the invention,—

Figure 1 is a side elevation of the working parts of the Schrader valve, illustrating the invention, the shell or casing being shown in section.

50 Fig. 2 is a longitudinal sectional view of Fig. 1.

Fig. 3 is a vertical section in a plane at right angles to Fig. 2.

Referring to the drawings, let A indicate 55 the casing of a valve shell having screwed in

its outer end a plug B which screws entirely within the shell which is swiveled to a valve seat C, the latter having a packing washer D designed to contact with the tapered walls of the casing to form an air 60 tight joint between the two. The valve proper is indicated at E being carried upon a pin F which passes upwardly through the seat member C and plug B to a point near the top of the valve, as best indicated 65 in Fig. 2. Below the valve proper is a loading spring G, the lower end of which engages the top of a cup-shaped guide H. The lower end of the pin E passes through the cup H and is guided in its movements 70 by the latter.

According to the present invention the plug B is provided with a bridge J which extends the full diameter of the bridge in one direction while in a direction at right 75 angles thereto it is sufficiently narrow to be engaged by a slotted valve cap to form a means for screwing in and unscrewing the plug. The plug B is formed on its interior with a bore or opening K which should be 80 of as large diameter as possible in order to permit the maximum quantity of air to pass through the plug. In prior constructions this bore has been carried the full length of the plug with the effect that the top of 85 the pin E has not been efficiently guided since it was capable of tilting to a considerable extent, thus permitting the valve proper E to tilt to a slight degree on its seat. The bridge J according to the present in- 90 vention is provided with a hole or aperture L which is of slightly larger diameter than the pin E so that while the latter may slide freely through it it nevertheless is accurately guided. The passage thus formed 95 between the bridge and pin is very small and would not be sufficient to permit the inflow or outflow of the air with sufficient rapidity in practice. To provide the necessary passage openings N are provided pref- 100 erably on both sides of the bridge which extend upwardly, so that when the plug is screwed into the valve shell they will not be covered by the shell. This is best seen in Fig. 3. In constructing the parts the plug is drilled from the bottom to the proper point and a smaller drill is then run through the bridge L either from the top or the bottom. The metal is cut away at N 105 (Fig. 3) at the sides of the plug to form 110

the lateral walls of the bridge either before or after the drilling operations, or between the two drilling operations, as desired.

The invention is applicable to other constructions than that shown, wherein the plug and valve seat are made as separate parts. The invention is also capable of various modifications.

I claim as my invention:—

- 10 1. In a valve for tires or the like, the combination of a shell, a plug screwing in said shell, a valve proper beneath said plug, a pin extending upwardly from said valve proper through the plug, and said plug having a bridge for guiding the upper end of said pin, and having openings at its top on each side of said bridge.
- 15 2. In a valve for tires or the like, the combination of a shell, a plug screwing in said shell, said plug having a bore of larger diameter formed therein, a bridge above said bore having a hole of smaller diameter than said bore, and said plug having a lateral passage to said bore beneath said bridge, said passage opening at the top of said plug, and a valve proper having a pin extending upwardly through said bore and bridge.
- 20 3. For tire valves or the like, a plug having a bore passing partly through it, a bridge above said bore and having a hole of less diameter than said bore, and said plug having a lateral passage to said bore, said passage opening at the top of said plug.
- 25 4. For tire valves or the like, a plug having a bore passing partly through it, a bridge above said bore and having a hole of less diameter than said bore, and said plug

having a lateral passage to said bore, said passage opening at the top of said plug in combination with a valve proper having a 40 pin extending through said bore and bridge.

5. In a valve for tires or the like the combination of a shell, a plug screwing into said shell, a valve proper beneath said plug, and said plug having a screw-driver projection extending completely across the top thereof, at its middle.

6. In a valve for tires or the like, the combination of a shell, a plug screwing into said shell, a valve proper beneath said plug, said plug having a screw-driver projection extending completely across the top thereof at its middle, and a pin on the said valve proper extending through a hole in said screw-driver projection.

7. In a valve for tires or the like, a plug having a bore and a screw-driver projection extending across the top of said bore from one side of the plug to the other.

8. In a valve for tires or the like, a plug having a bore and a screw-driver projection extending across the top of said bore from one side of the plug to the other, and a valve proper below said plug having a pin extending upwardly through said screw- 65 driver projection.

In witness whereof, I have hereunto signed my name in the presence of two subscribing witnesses.

HENRY P. KRAFT.
